UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed March 24, 1927. Serial No. 177,884.

This invention relates to typewriting machines of that class where an auxiliary ink-ing ribbon, interposed between superposed work-sheets, is employed to manifold a record-sheet with permanent characters, and the present invention can be regarded as an improvement on my two pending applications, one filed January 5, 1927, Serial No. 159,046, and the other filed March 18, 1927, Serial No. 176,360, that include methods of mounting a ribbon-spool at each end of the carriage above the platen, feeding the ribbon from spool to spool at each actuation of the line-space mechanism, directing the ribbon from each spool to the typing line, and providing a protective tape to prevent offsetting of the characters upon the outer work-sheet.

Features of improvement in the present invention include a simplified ribbon-spool and the manner of demountably suspending the spool within its housing; a simplified ribbon-spool-driving connection to the line-spacing-devices; a novel manner for alternately rendering each spool operative to feed the ribbon over the typing line in opposite directions; ribbon-clamping means operative at all times to prevent the formation of a slack in the longitudinal stretch of the ribbon over the typing line, except during the interval of line-spacing the platen when the feeding of the ribbon takes place; protective devices to cover the ribbon that are adjustable to the width and position of the outer work-sheet; means automatically operable by the shifting of the ribbon to inoperative positions to disconnect the spool-feeding mechanism from the line-spacing mechanism; means operably connectible to the ribbon-shifting mechanism to simultaneously raise a pair of paper-holding devices from the face of the platen; a center support adjustable along the carriage to prevent sagging of the ribbon between the ribbon-carriers positioned at each end of the carriage; a ribbon-clamping device automatically released by the line-spacing mechanism or manually released at will; paper-holding devices actuated by the ribbon-shifting mechanism to automatically raise the devices when the auxiliary ribbon is shifted clear of the platen

for the adjustment of a wide record-sheet; and ribbon-guides at each end of the typing line operable to deflect the fixed plane of the ribbon at the typing line to the fixed feeding plane of the ribbon-spools, and adjustably mounted to compensate for variations in the assembly of the parts to establish a uniform tension at both edges of the ribbon, to hold the ribbon in a flat state during its travel from spool to spool.

No claim is herein made to cover broadly any feature disclosed in co-pending applications of Hausman, No. 118,740, filed June 26, 1926, and No. 755,915, filed December 15, 1924.

Other features and advantages will hereinafter appear.

In the accompanying drawings.

Figure 1 is a perspective view of the platen and portions of the carriage-frame illustrating the manner of assembling the auxiliary ribbon-feeding and ribbon-controlling mechanisms upon the carriage-ends, including connections from the line-spacing lever to feed the ribbon-spools, ribbon-shifting connections operable to raise the ribbon above the typing line, and other connections operable to automatically connect and disconnect the ribbon-spool-driving mechanism from the line-spacing mechanism.

Figure 2 is a full-size sectional view through the left-hand ribbon-spool, showing the details of construction for demountably securing the spool within the spool-housing.

Figure 3 is a full-size view of one of the carriers that suspends a protective tape over the face of the ribbon, and also operates as a center support for the auxiliary ribbon.

Figure 4 shows a modified form of control for a rock-shaft carrying paper-fingers operable above the typing line to hold a wide work-sheet against the platen-face.

Figure 5 shows the same mechanism as Figure 4 shifted to a position where the rocking of the shaft raises the paper-fingers to inoperative positions.

Figure 6 is a full-size front elevation of the platen-carriage ends and ribbon-spool mountings at each side of the carriage, the view being condensed by breaking away the

middle sections of the platen and carriage. Figure 7 is a reduced view of the left-hand end of the carriage with portions of the frame broken away, and the ribbon-shifting mechanism relatively positioned where the auxiliary ribbon is raised above the typing line and close to the face of the platen.

Figure 8 shows some of the parts of Figure 7 shifted to extreme raised positions where the auxiliary ribbon has been shifted from the position of Figure 7, to remove the ribbon to a clearance position for the front insertion of a work-sheet.

Figure 9 is a full-size view of the left-hand carriage-end, showing all the connecting mechanisms in normal positions with the auxiliary ribbon covering the typing line.

Figure 10 is a skeleton view of the left-hand ribbon-spool and its feeding mechanism actuated by the initial movement of the line-space lever to bring the ribbon-spool-driving pawl into engagement with the spool-driving ratchet-wheel, and the auxiliary ribbon-clamping elements released to free the ribbon before any spool-feeding movement is conveyed to the pawl to feed the auxiliary ribbon.

Figure 11 is a full-size vertical cross-sectional view through the platen and carriage, looking towards the right-hand ribbon-spool, with the several parts in normal or operative positions.

Figure 12 is a view drawn to the same scale as Figure 10, and showing the same parts positioned at the end of the line-space movement where a ribbon-feeding movement has taken place, and the auxiliary ribbon-clamping elements have been restored before the ribbon-spool is released from its driving pawl.

40 Figure 13 is a view of the left-hand carriage-end showing the several parts in normal positions ready for typing and manifolding a line-record, both primary and auxiliary ribbons assuming parallel vertical planes
45 over the typing line, and the auxiliary paper-fingers in operative position to hold and direct the aligned record-sheet to the rear of the platen.

Figure 14 shows the parts of Figure 13 raised to the sheet-inserting position, where the feed-rolls are released from the platen and the paper-fingers lifted, so that the work-sheet, when inserted at the rear of the platen, will have a clear passage across the typing line to be deflected under the paper fingers.

60 Figures 15, 16 and 17 are operational views, showing the paper-fingers and their controlling connection at three different positions relatively to the platen; Figure 15 shows the normal position of the paper-finger and its connection to the manually-operated rock-shaft; Figure 16 shows the paper-fingers in operative relation to the platen, but 65 the connection to the rock-shaft has been

shifted by the raising of the auxiliary ribbon above the typing line; and Figure 16 shows the paper-fingers raised away from the platen through a continued movement of the connection to the rock-shaft when the auxiliary ribbon is raised clear of the platen prior to the insertion of a work-sheet.

Figure 18 is a view, in perspective, showing the ribbon-shifting rock-shaft and the connection from said shaft to the rockable shaft carrying the two paper-fingers. The view also shows in detail the manner of assembling the paper-fingers to their rock-shaft, and also shows the relation of the paper-fingers to the several work-sheets and auxiliary ribbon. 75 80

The platen 20 rotates with a platen-shaft 21 having bearings within carriage-ends 22 and provided with a line-spacing mechanism including a line-spacing lever 23, engageable to operate a slide-bar 24, carrying a pawl 25, operative to engage with the teeth of a ratchet-wheel 26 secured to the shaft 21 to rotate the platen a line-space distance at each actuation of the lever 23. 90

The carriage-ends 22 are joined together at the rear of the platen by the usual paper-table 27 that curves under the platen to serve as a paper-deflector to guide work-sheets to the typing line or to guide work-sheets under the platen towards the rear when a sheet is collated by a front insertion. 95

A bracket 28 is secured to each carriage-end 22 by screws 29, to provide bearings at each end of the carriage for a ribbon-feeding driving shaft 30, a ribbon-feeding rock-shaft 31, a ribbon-feeding rock-shaft 31¹, and a paper-finger rock shaft 32, all mounted parallel to the platen. 100

The shaft 30, next to the offset face of the left-hand bracket 28, has a one-way ratchet-wheel 33 secured thereto and provided with a driving means including a lever 34 fulcrumed upon the shaft between the ratchet-wheel 33 and a collar 35, and having an arm 36 supporting a pawl 37 pivoted thereupon and provided with a spring 38 to hold the pawl in operative engagement with the teeth 105 110

power in positive engagement with the teeth of the ratchet-wheel 33 at all times to drive the ratchet and shaft 30 in a positive direction, assured by a suitable spring-pressed check-pawl 39 engaging said ratchet. The arm 36 has a pivotal connection to one end of a link 40 pivotally connected to the rear end of the slide-bar 24 of the line-spacing mechanism, all the connecting parts being held in normal positions under the tension of a spring 41 that restores the bar, after each line-spacing movement, against the stop on the frame in the usual Underwood manner. The spacing movement of the bar 24 operating through the link 40 vibrates the arm 36 to swing the pawl 37 to rotate the ratchet-wheel 33 and shaft 30 one tooth distance to swing the lever 34 forwardly. The free end of the 130

lever 34 carries a shouldered stud 42 to engage within a slot formed in the end of an inverted L-shaped lever 43 having a fulcrum upon a long shouldered stud 44 carried upon the end of an arm 45 adjustably secured to the shaft 31^a. The adjustment of the parts is such that when the stud 42 and the lever 43 are at their normal positions a vibratory movement of the lever 43 will withdraw the slot in the end thereof from the stud 42, as shown in Figure 7, and should a vibratory movement be conveyed to the lever 34 in line-spacing, no movement will be conveyed by the stud 42 to the lever 43. When the lever 34 is vibrated in line-spacing and the stud 42 is seated in the slot at the end of the lever 43, the forward swing of said lever 34 will raise the lever 43 forwardly to rock the shaft 31^a and its connections for purposes to appear.

The brackets 28 may be formed with ears 46 at the front edge thereof, upon which there is mounted a cross-bar 47 secured by screws 48 and arranged parallel to the platen. Upon this bar 47 adjacent the carriage-ends there are mounted U-shaped ribbon-spool brackets 49 and 50, each bracket formed with parallel side walls 51 and 52, and between the upper ends of the side walls there are housed ribbon-spools 53 and 54, respectively, upon spool-shafts 55.

The connections of both ribbon-spools 53 and 54 and their controlling and feeding mechanisms are identical, except for the right and left hand assembly of the parts, and the description of one spool and its connecting mechanism will also be descriptive of the companion spool. A spacing washer 56 is staked to the side wall 52 of the bracket 49 and tapped centrally to receive the threaded end of the shaft 55. A bearing stud 57 is staked to the wall 51 to project inwardly and provide a support for the opposite end of the shaft, the shaft having a knurled head 58 shouldered down to bear against the wall 51 and operate to draw the two walls 51 and 52 together. A sleeve 59, slidably assembled over the stud 57, is provided with a flange 60 at one end and a spring 61 compressible between said flange and the face of the wall 51. The ribbon-spool includes heads secured to a core 62 slidably mounted upon a sleeve 63 secured to a ratchet-wheel 64 provided with a driving pin 65 aligned to a hole 66 passing through the core 62 to render the spool interchangeable with either bracket 49 or 50. At Figure 2, the ribbon-spool has been removed from the bracket, and the sleeve 59 is shown spring-pressed towards the wall 52 of the bracket, and to prevent the sleeve from wholly separating itself from the stud 57, one end of the spring 61 may be soldered to the flange 60 and the other end of said spring may be soldered to the face of the wall 51, the soldering of the ends of the spring also preventing

turning of the sleeve 59 upon the stud 57. To adjust the spool to the conditions shown at Figure 2, the sleeve 59 is pushed leftward compressing the spring 61, and the spool and its ratchet 64 adjusted between the flange 60 and the washer 56, when the shaft 55 is passed through the stud 57 and the sleeve 59, and threaded into the wall 52. The spool and the ratchet-wheel 64 are rotatable upon the shaft 55 under a certain restraint from the stationary spring-pressed flange 60 bearing against the face of the ratchet.

To rotate a ribbon-spool and draw the ribbon across the typing position, there is provided a crank-arm 67 adjustably secured to the rock-shaft 31^a and carrying a feeding pawl 68 on the end thereof formed with a tooth 69 engageable with the teeth of the ratchet-wheel at the side of the ribbon-spool, and an arm 70 having a stop-pin 71 normally engaging the edge of the arm 67 under the tension of a spring 72 flexed between the pin 71 and a similar pin 73 upon the arm 67. The normal position of the pawl, determined by the pin 71, holds the tooth 69 of the pawl clear of the ratchet-teeth but the initial forward movement of the arm 67 swings the tooth into feeding engagement with the ratchet. From this description, it will be understood that the rocking of the shaft 31^a by the line-spacing mechanism operates to swing the pawl 68 in a ratchet-feeding direction to rotate the ribbon-spool.

As there is a crank-arm 67 and a pawl 68 secured to each end of the shaft 31^a to rotate both spools 53 and 54, it is necessary to provide means to silence one pawl-fed spool while the opposite pawl is operative to feed a ribbon-spool. It will be remembered that the pin 71 operates to normally hold its associated pawl 68 out of operative engagement with the ratchet 64, and with the teeth of both pawls bent in opposite directions, as shown, and so spaced relatively to the spaced-off spools that when one pawl is operative at the spool 54, the opposite pawl is inoperative at the spool 53, and as shown at Figure 6, the shifting of the rock-shaft 31^a in the direction of its axis reverses the positions of the pawls relatively to the spools. To this end, the shaft 31^a is provided with a stop-collar 74 to abut the face of the left-hand bracket 28 to locate the pawl 68 to the spool 54, while a hub 75 will arrest the rightward shift of said shaft 31^a to render the pawl 68 inoperative to the spool 54 and render the opposite pawl 68 operative to feed the spool 53. To lock the shaft 31^a at either of the shifted positions, the hub 75 may include a V-shaped disk 76 that co-operates with a V-shaped spring 77 secured to the adjacent bracket 28, said disk riding under the spring to either side of the V thereon, and the spring not interfering with the rocking of the shaft 31^a. The free ends of the shaft 31^a outside the

bracket 28 may be provided with convenient push-buttons 78. It will be noted that the long stud 44, which is shifted with the shaft 31^a and has a fulcrum on the lever 43, does not interfere with the operation of said lever at either shifted position of said shaft.

Upon the front face of the bar 47 there are secured by screws 48 the feet of a pair of brackets 79, one bracket positioned adjacent 10 each end of the carriage and each bracket formed with an arcuate slot 80 concentric with the shaft 31, and a compound slot formed by the merging of two arcuate slots 81 and 82. Forwardly-extending crank-arms 15 83 are secured to the rock-shaft 31 to align with the side face of each bracket 79, with the free ends provided with studs 84 that pass through the slots 80 to pivotally support the upper ends of a pair of vertically-disposed 20 arms 85, each arm being held upon one stud 84 and against the adjacent face of a bracket 79 by screws 86 threaded into the studs. The lower terminals of the arms 85 carry shouldered studs 87 that pass through slots 82 and 25 88 are slidably held against the faces of the brackets 79 by the heads of the studs bearing against the opposite faces of said arms.

The arms 85 are formed with extensions 30 bent over at the ends to form feet 89 that may be secured to the ends of a cross-bar by screws 91. These two arms 85 secured to the ends of a bar 90 form a cradle that is rockable to varying positions through the pivotal connections to the arms 83 and the joint 35 effect of the studs 87 following a path directed by the two slots 82.

At each end of the bar 90 there is mounted a ribbon-carrying and ribbon-guiding plate 40 92 formed with a ribbon-deflecting angular slot 93 aligned to the vertical planes of the ribbon-spools 53 and 54. These plates 92 depend from the bar 90 to present a horizontal section of the auxiliary ribbon to the typing line.

45 It is a well-known fact that the typing along the edge of a ribbon tends to stretch the fabric of the ribbon along that edge, and while one edge remains taut between the ribbon-carriers, the top edge becomes slack and 50 puckered, and interferes more or less with the rapid insertion of superposed work-sheets. To remedy this defect, each plate 92 is suspended from the bar 90 by a pin 94 at one edge thereof and formed with elongated 55 holes 95 at the opposite edge for the screws 91. When the screws 91 are loosened, the plate may be rocked about its pin 94 to change the relative angularity of the slot 93 that operates to take up any slack at either edge 60 of the ribbon. If this adjustment becomes frequent the two screws 91 may be displaced by a thumb-screw. Each plate 92 is formed with an offset 96 to position the ribbon-carrying slot 93 in a plane tangent to the typing 65 axis of the platen, instead of pitching the

ribbon slightly towards the rear as heretofore. The effect of this arrangement holds the auxiliary ribbon close to the platen and parallel with the main typing ribbon vibrated to cover the typing line.

70 The rock-shaft 31, preferably at the right-hand end thereof, may be provided with an operating lever 97 secured thereto and formed with a finger-piece 98. The raising of the finger-piece 98 results in rocking the shaft 31 to raise the arms 83 to advance the studs 84 along the clearance slot 80, to lift the ribbon-carrying cradle 85, 90 and advance the studs 87 along the guide-slots 82 from the normal position of Figure 11 to the positions shown at Figure 7. The curvature of the slots 82 co-operating with the arcuate paths of the studs 84 results in holding the ribbon close to the face of the platen at both the operative and inoperative shift-positions thereof, clearly 80 shown at Figure 7.

85 Each arm 85 of the ribbon-cradle is formed with a cam-face 99 which, when positioned as at Figure 7, is about to engage with a pin 100 in the fixed bracket 79. Should the lever 97 be raised from the Figure 7 position to the position of Figure 8, it will be noted that the stud 87 is close to the upper end of the slot 82, and further movement of the stud will be blocked by the edge of the slot 95 81, which is nearly at right angles to the direction of the slot 82, and the further actuation of the lever 97 would be difficult, if not impossible. To overcome this condition, which could not be remedied by any angular readjustment of the two slots 81 and 82, each arm 85 engages the pins 100 to cam the lower ends of said arms and direct the swing of the studs 87 to the curvature of the slots 81, and thus remove any frictional 100 contact between studs 87 and the sides of said slots 81 when the lever 97 is swung to the position of Figure 8 to rock the auxiliary ribbon forwardly and upwardly, as when a work-sheet is removed, or a new sheet adjusted around the platen. It will be remembered that the cradling ribbon-carrier is suspended from the arms 83, and an interruptive swinging movement is given to the carrier by the slots 82, and by the cam-faces 99. The two slots 80 and 81 are clearance slots within 105 the two brackets 79, and primarily prevent endwise movement of the ribbon-carrier slidably assembled between the brackets.

110 The arm 83 at the left-hand end of the carriage has a shouldered screw or stud 101 at the side thereof to pass through a slot 102 in the forward end of the lever 43. When the lever 43 is positioned as at Figures 1 and 9, the actuation of the line-space lever 23 will cause the lever 34 to swing the lever 43 to rock the shaft 31^a and effect a pawl-feeding movement to one ribbon-spool. Said lever 43, during its swing with the shaft 31^a, causes its slotted forward end to slide under the 115 120 125

head of the stud 101, as shown at Figure 12. When the lever 97 is raised to the position of Figure 7 to shift the ribbon to the inoperative position, the stud 101 has traveled along the slot 102, and the lever 43 has been vibrated about its fulcrum 44 to withdraw the slotted end thereof from the stud 42, and line-spacing movements given to the platen during the interval the ribbon is inoperative will idly vibrate the lever 34 and will not effect a ribbon-feeding movement of the winding-up ribbon-spool.

To control the slack in the ribbon when the ribbon carrier is raised by the lever 97, fingers 103 may be secured to the face of the cross-bar 47 adjacent each ribbon-section between the spools and the ribbon-carrier.

When the ribbon-carrier is shifted to the position of Figure 7, a slack exists in the ribbon and when any slack appears in the longitudinal stretch of the ribbon between the two carriers the operator is never sure that the auxiliary ribbon really covers the typing line, especially at the center thereof. Means here-20 to have been provided to clamp or retard the ribbon at some point between the spools and the carriers to prevent this slack from entering the line-typing section of the ribbon. But these ribbon-clamps depend upon an initial movement of the ribbon-carrier before the clamps become effective, and the ribbon is really loose before it is clamped.

In the present construction, there is provided a bracket 104 secured to the bar 90 adjacent the inner edge of each vertical section Y and Z of the ribbon X to support ribbon-clamping levers 105 upon pivots 106, each lever including a finger 107 bent at right angles to overlie the ribbon at a point over the offset face 96 of each plate 92, a finger-piece 108 at the upper end of said lever and a tail-piece 109 passing over the edge of the cross-bar 90 to the rear thereof. A spring 110, under tension between a pin on the lever 105 and a pin on the bracket 104, operates to normally hold each finger 107 in clamping engagement against the ribbon and against the offset faces 96, and always holds the ribbon clamped to the plates 92 regardless of the shifted position of the ribbon-carrier, and hence there is no mechanism to be finely timed to any part of the ribbon-shifting mechanism before the ribbon is clamped to prevent a slack in the ribbon across the typing line. While the ribbon-feeding mechanism, actuated by the line-space lever, is operative to draw the ribbon under the two clamping fingers 107, it is desirable to relieve the line-space lever of this unnecessary burden, and means are provided whereby the forward line-spacing stroke will automatically release the ribbon-clamps before a ribbon-feeding movement, and automatically re-60 store the clamps at the end of the line-space

operation and after the feed of the ribbon has taken place.

It will be remembered that at each actuation of the line-space lever 23 the pawl 37 rotates the ratchet 33 one tooth-distance to drive the shaft 30. Upon the shaft 30, adjacent the inner walls 52 of the spool-brackets 49 and 50 there is secured a pair of camming disks 111 having a number of camming grooves 112 equal to the number of teeth in the ratchet 33. A lever 113 hangs pendent from a pivot-screw 114 threaded into the side walls 52, and the lower end of each lever 113 may be formed with a bent-over finger 115 to normally abut the tail 109 of the clamping lever 105. Each lever 113 has a pin 116 timed to normally drop into a groove 112 in the adjoining disk 111. When the shaft 30 is rotated one tooth-distance the initial movement thereof causes each pin 116 to ride out of a groove 112 and upon the periphery of disks, and said pin operates to vibrate its lever 113 to press upon its tail-piece 109 to vibrate the levers 105 and release the ribbon at both plates 92. This releasing movement takes place while the pawl 68 is moving into engagement with the ribbon-spool ratchet and before any ribbon-feeding movement takes place. At the end of the line-spacing stroke the pins 116 will ride off the periphery of the disks 111 into the advancing groove 112, and the levers 105 will be released to the action of their springs 110 to reclamp the ribbon to the plates 92 before the ribbon-feeding spool is released by the return movement of the pawl 68.

While the ribbon is clamped at all times except during the spool-feeding interval, one or both ribbon-sections may be released at will by a manual depression of either finger-piece 108.

Both ends of the shaft 31, outside the brackets 28, may have secured thereto a detent sector 117 formed with three detent grooves 118, 119 and 120. To coact with these grooves a pawl 121 is pivoted upon the face of each bracket 28 and actuated by a spring 122 to engage within the grooves when the sector 117 is rocked with the shaft, the groove 118 indicating the position of the shaft where the ribbon normally covers the typing line, the groove 119 indicating the position of the ribbon-vibrator raised to the position of Figure 7, and the groove 120 becoming operative to hold the shaft and its associated parts in the positions of Figure 8.

The platen may be provided with collating tables 123 of well-known form, and sheet-feeding rollers 124 to feed a wide record-sheet B next to the platen, and a narrow superposed work-sheet C, the auxiliary ribbon X being operable between the two sheets to manifold the record-sheet and the regular inked ribbon 125 to type upon the narrow outer work-sheet. To prevent the auxiliary ribbon X from offsetting upon the back face of the outer sheet, 125

a protective device in the form of a tape 126 is interposed over the ribbon and between the ribbon and the sheet C. The method of suspending the tape over the face of the ribbon, and at the same time adjusting the length of the tape to the width and relative position of the narrow superposed sheet C, includes a pair of carriers 127 adjustably mounted upon the bar 90. Each carrier 127 is formed with an angular slot 128 to turn the ends of the horizontally-disposed tape at right angles to pass over the bar 90 and under a clamping tongue 129 forming a part of the carrier, to be clamped there-between by a thumb-screw 130 threaded into the bar 90. The carrier 127 may have its top edge bent at right angles at 131 to ride along the top edge of the bar 90. With such a construction the tape may be placed under a considerable tension between 20 the two carriers without developing a strain in the ribbon-carrying ends.

The adjustment of the length of the tape to the width of the narrow work-sheet provides for a comparatively short stretch of tape between the two carriers 127, and little trouble is experienced from the sagging of the tape. The long stretch of the ribbon, however, between the two plates 92 adjusted to a wide carriage, is considerable, and to prevent the 30 sagging of the ribbon the spool-brakes must be placed under an excessive tension which the line-spacing mechanism must overcome in feeding the ribbon-spool. To remove this tendency of the ribbon to sag, and reduce the drag at the spool and correspondingly reduce the line-spacing resistance, the tape-carrier 127 positioned at the right-hand side of the narrow sheet C may be formed with a vertical slot 135. The auxiliary ribbon may be adjusted in front of a tongue 136 to enter the vertical slot 135, and then pass to the rear of the carrier 127 to provide a center support for the auxiliary ribbon X and practically prevent any sag in the ribbon. In this manner the protective tape-carrier 127 also becomes a center support for the auxiliary ribbon.

A suitable tally-roll mechanism may be employed with the two work-sheets B and C when required. This mechanism includes a gear 132 on the drive-shaft 30 to drive a gear 133 and a spool 134 operative to wind up a tally-strip fed around the platen to receive abbreviated work-sheet records.

In certain forms of office records the wide work-sheet B may have paper-holding devices at the edges of the sheet to hold the sheet stationary to the platen after the feed-rolls have been cast off for the insertion of a superposed sheet C, and it is a desirable feature to provide means for automatically casting off these paper-holding devices when a typed ledger-sheet is to be renewed.

To this end the shaft 32 is converted into 65 a rock-shaft through the addition of a crank-

arm 137 secured to the left end of said shaft and connected by link 138 to an arm 139 forming a part of the sector 117. The paper-holding devices are adjustably mounted upon the shaft 32, each device including an arm 140, a paper-finger 141 and a roll 142. Each arm 140 is bent U-shaped at the rear to provide two widely separated bearings for the arm. Between the bearings a collar 143 is assembled upon the shaft 32, a metal strip 144 being secured to the collar, said strip having one edge 145 turned down to confine one bearing of the arm 140 between said edge and the collar and then enter a groove 146 cut longitudinally in the shaft 32. The strip 144 provides a means for securing one end of a spring 147 coiled about the shaft 32, with the opposite end hooked over the edge of the arm 140 to throw said arm towards the plate. The contact of the paper-finger 141 with the platen arrests the action of the spring 147, while an equalizing spring 148 is secured between the crank-arm 137 and a pin 149 on the bracket 28. The relation of the paper-finger to the shaft 32 is such that the part 145 that enters the groove 146 in the shaft 32 shall have a slight free movement to enable the spring 147 to actuate the paper-finger independently of the shaft 32, which is a well-known construction.

When the shift-lever 97 is raised from the normal position of Figure 13 to that of Figure 7, and while the ribbon is raised above the typing line, the connection 138 assumes the position of Figure 16 relative to the arm 137 and the paper-fingers are operative against the work-sheet B. When the lever 97 is raised to the position of Figure 14 and the auxiliary ribbon is swung clear of the platen, the connection 138 pushes the crank-arm 137 to the position of Figure 14 and the paper-fingers 141 are raised from the platen so as not to interfere with the insertion or withdrawal of the work-sheet.

Should it be found that the raising of the paper-fingers 141 with the ribbon-shifting mechanism be burdensome for the lever 97, a separate manual operation may be substituted for the automatic operation, of raising the fingers through the connecting link 138 and arm 137. At the right-hand end of the shaft 32 an actuating lever 150 may be secured thereto with the lower end connected by spring 151 to a pin 152 at the bracket 28. The upper end of the lever 150 may be bent over to form a finger-piece 153. The normal position of the lever 150 is determined by the interlock of a latch 154 pivotally hung at 155 at the side of the lever 150 to engage the pin 152 against the tension of the spring 151. The latch 154 includes a finger-piece 156, a groove or seat 157, and spring 158 operating to hold the latch against the pin 152 as shown in Figure 4. When it is desired to raise the fingers 141 from the position 130

of Figure 4 to the position of Figure 5, the finger-piece 156 of the latch 154 is pushed rearwardly to swing about its pivot 155 until the pin 152 seats within the groove 157 at 5 the lower end thereof when the latch will swing about the pin 152 as a fulcrum, and, through the pivotal connection 155 to the lever 150, said lever will be forced rearwardly in unison with the latch 154 to rock the shaft 10 32 and raise the paper-fingers 141 until the edge of the arm 140 strikes the pin 152 to arrest the movement. The relation of the parts is such that the spring 151 becomes operative to hold the arm 140 indefinitely against 15 the pin 152. To restore the paper-finger, the two finger-pieces 156 and 153 are pinched between the fingers and simultaneously drawn forwardly to withdraw the seat 157 from the pin 152 by flexing the spring 151 and 20 rocking shaft 32 until the pin enters the normal seat 159 of the latch 154, which effectively holds the shaft 32 in the normal positions of Figure 4.

The introduction of each work-sheet separately may be facilitated by the usual guide-finger (not shown) extending up in front of the platen and work-table, and the usual card-guide (not shown) at the front of the platen.

30 In adjusting the work-sheets to the platen for typing, the lever 97 is first raised to the position of Figure 8 to remove the auxiliary ribbon. The connection 138 simultaneously rocks the shaft 32 to lift the paper-fingers 141 as shown at Figure 17. The usual platen-fed rollers 124 having been released, the work-sheet B may be inserted at the rear of the platen and pushed under and around the front of the platen and aligned to the collating table 35 123 and to the typing line, when the lever 97 is depressed to the position of Figure 7 to simultaneously lower the auxiliary ribbon to the platen-face and lower the paper-finger into operative engagement with the work-sheet to prevent displacement thereof during 40 the introduction of the outer sheet C which may be adjusted around the platen from the front to overlie the sheet B, and the feed-rolls 124 are now restored. The lever 97 may 45 now be depressed to the normal operative position to lower the auxiliary ribbon X and its protective tape 126 to the typing line and between the two work-sheets. After typing the line, both sheets may be line-spaced and, 50 through the connections to the line-spacing mechanism, the ribbon-clamps 107 release the ribbon, the winding-up spool draws a section of ribbon along the typing line, and, at the end of the line-space movement, the 55 clamps 107 are restored into ribbon-clamping positions. This single-line entry usually finishes the typing operation for the outer work-sheet. The lever 97 is raised to the position of Figure 7, the ribbon raised to an inoperative 60 position, the feed-rolls 124 cast off, the 65

typed sheet removed to be replaced by another, and the operation repeated. It will be particularly noted that in shifting the auxiliary ribbon to the inoperative position of Figure 7 during the removal or adjustment of the outer sheet C, the sheet B is held stationary with the platen by the paper-fingers 141, which are not raised until the lever 97 is lifted to the Figure 8 position for renewing the wide sheet positioned next to the platen. 75

While the preferred form of the present invention includes means for manifolding upon a record-sheet, other forms of office practice may require a third sheet, as shown in Figure 18. Here, an extra wide ledger or other sheet A is adjusted around the platen with a carbon-sheet overlay A', as shown, to be held in operative position upon the platen by the paper-fingers 141. The sheet B may be collated over the carbon-sheet A' and under 80 the auxiliary ribbon, and a third sheet may be collated over A' and B outside the auxiliary ribbon. Thus in typing a single-line entry upon the sheet C, the characters are manifolded through the auxiliary ribbon to the sheet B 85 and manifolded through the carbon-sheet A' to the ledger-sheet A. When the ribbon is raised to its inoperative position before the removal of the two sheets B and C, the paper-fingers 90 141 hold the sheet A and carbon overlay A' 95 against displacement.

Should it be required that both sheets A and B be continuous record-sheets, one manifolde by ribbon and the other by carbon, both the sheets A and B may be positioned edge to 100 edge at the left hand to come under the control of the left-hand paper-finger of Figure 18, or other fingers 141 may be assembled upon the shaft 32 to engage the side edges of the sheet B. 105

If the manual control of the shaft 32 and the fingers 141 by the finger-pieces 153 and 156 be employed and the connection 138 to the ribbon-shifting mechanism removed, the paper-fingers in holding the sheets A and 110 A' permit the auxiliary ribbon to be shifted to the position of Figure 8 when the two sheets B and C may be collated together or differentially and then clamped by the feed-rolls 124 in their relative adjusted positions, when the 115 sheet C may be swung forwardly to clear the auxiliary ribbon in shifting to the typing line between the two work-sheets B and C. 120

It will be noted that the sheet A may be a very wide work-sheet requiring a twenty-four-inch platen to accommodate it. The outer sheet C will be very much narrower, which leaves a considerable stretch of ribbon at the right-hand side of the sheet C uncovered, and, in preventing this wide stretch 125 of ribbon developing a sag through the employment of a center support for the ribbon relieves the mind of the operator of the possibility of a semi-manifolded record.

The center support for the ribbon is shown 130

and described as forming a part of one tape-carrier, but it will be understood that a duplicate carrier 127 may be adjusted along the rail as a center support for a long auxiliary ribbon without being used jointly as a tape-supporting member.

It will be noted that the spool-feeding pawls are duplicates and that both pawls are rocked by the shaft; that the spread of the pawls along the shaft 31^a is greater than the spread of the spools on the carriage; that each pawl is rendered operative or inoperative in alternation by the longitudinal shifting of the shaft 31^a to bring one pawl into cooperation with a spool; that the side arms 85, cross bar 90 and ribbon-guide plates 92 form a ribbon-carrier operable to control the position of the ribbon relatively to the typing line; that said ribbon-carrier is wholly suspended from the arms 83; that said carrier is given a cradling movement in approximately opposite directions, one direction up and around the face of the platen and then in a forward direction away from the platen; that this cradling movement of said carrier is directed by fixed guides on the carriage cooperative with the swing movement of the arms that suspend the carrier; that the auxiliary ribbon has a center support adjustable along the carriage; that the auxiliary ribbon is clamped at all times under tension except during the feeding thereof by the line-spacing mechanism; that said ribbon-clamping means are mounted upon the ribbon-carrier and remain operative to hold the ribbon under tension at all shifted positions of said carrier; that the clamping of the ribbon takes place at the ribbon-guides to reduce the length of ribbon to be clamped to a minimum; that the ribbon-clamping means have connections to the line-spacing mechanism that become operative to release the ribbon before the spool-feeding pawl feeds the spool and are restored to clamping positions before said pawl releases the spool at the initial return movement of the line-spacing mechanism; that the ribbon-feeding mechanism is operated by an intermediary 43 between the ribbon-shifting arm 83 and the line-space driven lever 34, said intermediary being operable to convey movement to the pawl to feed a ribbon-spool or operable by the shifting motion of the ribbon-carrier to sever the connection between said intermediary and the line-space actuated lever; and that the shafts 30, 31, 31^a and 32 are re-enforced midway of their lengths to maintain their parallel relation with the platen, by a spacing bracket 160 secured to the rear face of the bar 47.

It will be noted further that normally the extent of ribbon-feed is determined by the extent of line-spacing throw of the line-space mechanism; that should it be desirable for any purpose to feed the ribbon between the work-sheets an unlimited extent, either knob

78 may be rotated to vibrate the lever 34, rock the shaft 30 and disks 101, to vibrate the levers 113, to actuate the clamping levers 105, to release the ribbon, and while a knob 78 is thus held by one hand, the feeding spool may be manually turned in a ribbon-feeding direction and an unlimited extent of ribbon may be drawn along the typing line; that both knobs 78 may be rotated in unison by both hands, to release the ribbon and the feeding spool rotated the same extent as by the line-space mechanism; that this manual operation may be repeated indefinitely to release and feed the ribbon between the stationary work-sheets and without actuating the line-space mechanism; that said manual rotary operation of the knobs may be accompanied by a shaft-sliding movement to jointly establish a feeding direction for the ribbon; that the cross-bar of the ribbon-carrier at 85 the Figure 11 or typing position becomes a work-sheet deflector for the undermost or record-sheet; and that said cross-bar by its rectangular form in the Figure 7 position holds the record-sheet wrapped around the 90 platen and under sufficient tension to permit the adjustment of the outer work-sheet with the feed-rolls 124 thrown off and the paper-fingers 141 not employed.

Variations may be resorted to within the 95 scope of the invention, and portions of the improvements may be used without others.

Having thus described my invention, I claim:

1. In a front-strike typewriting machine, 100 the combination with a carriage having a platen, a ribbon-spool, and an angle guide over which the ribbon folds to travel along the platen, of means for enabling the tightening of the worn edge-portion of the ribbon 105 where it extends along the platen, including means on the carriage for affording adjustment of the angle guide to tension the worn edge of the ribbon to keep the ribbon in a flat condition, while maintaining said ribbon in 110 an unchanged operative position at the front of the platen.

2. In a front-strike typewriting machine, 115 the combination with a carriage having a platen, a ribbon-spool, a ribbon feedable by the spool, and a guide operable to deflect the feeding path of the ribbon from the spool to the typing line of the platen, of means for adjustably mounting the guide upon the carriage to justify the two angular paths of the 120 ribbon, at will, to maintain a uniform tension at both edges of the ribbon to prevent the ribbon from curling, while maintaining said ribbon in an unchanged operative position at the front of the platen.

3. In a front-strike typewriting machine, 125 the combination with a carriage having a platen, a ribbon-spool, and a ribbon feedable through a vertical path to the typing line, of a guide operable to deflect the path of the 130

ribbon from the spool to the horizontal plane of the typing line, said guide being adjustably mounted upon the carriage to take up any slack in either edge of the ribbon caused by variations in alignment of the assembled parts, while maintaining said ribbon in an unchanged operative position at the front of the platen.

4. In a front-strike typewriting machine, the combination with a carriage having a platen operable to feed a pair of superposed work-sheets, and a pair of ribbon-feeding spools disposed upon the carriage with one spool at each side of the work-sheets, of a pair of ribbon-deflectors movable with the carriage, one deflector under each spool and operable to change the path of the ribbon from its spool to the typing line between the work-sheets, each deflector being relatively adjustable to jointly equalize the tension at the edges of the ribbon along the typing line to present a flat-non-curling ribbon-face between the two work-sheets, while maintaining said ribbon in an unchanged operative position at the front of the platen.

5. In a front-strike typewriting machine, the combination with a carriage having a platen operable to feed a pair of superposed work-sheets, and a ribbon-spool at each side of the work-sheets operable to feed a ribbon in vertical paths to the typing line of the platen, of ribbon-guides pivotally supported upon the carriage and operable to change the direction of ribbon-feed from each spool to the typing line, each ribbon-guide including a compensating angular slot relatively shiftable to equalize any variations of tension in the two edges of the ribbon caused by wear to present a flat, non-curling ribbon-face between the two work-sheets, while maintaining said ribbon in an unchanged operative position at the front of the platen.

6. In a type-writing machine, the combination with a carriage having a platen, a ribbon-spool mounted at each end of the carriage, and a line-spacing mechanism operatively connected to line-space the platen and simultaneously feed a ribbon-spool of a ribbon-carrier operative to present the ribbon to the typing line, means normally operative to clamp the ribbon to the carrier, and means operatively connected to the line-spacing mechanism to release the ribbon-clamping means during the interval of feeding a ribbon-spool.

7. In a typewriting machine, the combination with a carriage having a platen, a ribbon-spool mounted at each end of the carriage, and a line-spacing mechanism operatively connected to line-space the platen and simultaneously feed a ribbon-spool, of a ribbon-carrier operative to present the ribbon to the typing line, means normally operative to clamp the ribbon to the carrier, and means connected to the line-spacing mechanism in-

itially operative to release the clamping means to free the ribbon for a spool-feeding movement and restore the ribbon-clamping means at the end of a line-spacing movement, to hold the ribbon under a ribbon-feeding tension.

8. In a typewriting machine, the combination with a carriage having a platen, a ribbon-spool mounted at each end of the carriage, and a line-spacing mechanism operatively connected to line-space the platen and simultaneously feed a ribbon-spool, of a ribbon-carrier operative to present the ribbon to the typing line, means normally operative to clamp the ribbon to the carrier, and means operable by a continuous line-spacing movement in advancing the platen, to release and restore the ribbon-clamping means, the interval between the two latter movements being timed to a spool-feeding movement to advance the ribbon between the clamping means.

9. In a typewriting machine, the combination with a carriage having a platen, a spool-fed ribbon, and a ribbon-carrier swingably mounted upon the carriage and operable to shift the ribbon to cover or uncover the typing line, of means operable to hold the ribbon under a predetermined tension at both shift positions thereof, said means including a pair of clamps operative to bind the ribbon to opposite ends of the ribbon-carrier.

10. In a typewriting machine, the combination with a carriage having a platen, a spool-fed ribbon, and a ribbon-carrier swingably mounted upon the carriage and operable to shift the ribbon to cover or uncover the typing line, of means operable to hold the ribbon under a predetermined tension at both shift positions thereof, said means including a pair of manually releasable clamps that normally are spring-pressed to bind the ribbon to opposite ends of the ribbon-carrier.

11. In a typewriting machine, the combination with a carriage having a platen, a spool-fed ribbon, a line-space mechanism, and a spool-feeding mechanism operatively connected to the line-space mechanism to feed a ribbon to the typing line at each line-spacing movement of the platen, of ribbon-clamping mechanism operative to hold the ribbon stationary under a spool-feeding tension; and means operable by the line-spacing of the platen to simultaneously release the clamped ribbon and rotate a spool to feed the ribbon, said ribbon-clamping mechanism including normally operative clamps and clamp-releasing members mounted upon the carriage, said releasing members being operatively connected to a part of the ribbon-spool-feeding mechanism.

12. In a typewriting machine, the combination with a carriage having a platen, a spool-fed ribbon, a line-space mechanism, and a spool-feeding mechanism operatively con-

- 5 nected to the line-space mechanism to feed a ribbon to the typing line at each line-spacing movement of the platen, of ribbon-clamping mechanism operative to hold the ribbon stationary under a spool-feeding tension, and means operable by the line-spacing of the platen to simultaneously release the clamped ribbon and rotate a spool to feed the ribbon, said ribbon-clamping mechanism including 70
- 10 normally operative clamps and clamp-releasing members mounted upon the carriage, each clamp-releasing member having separate connections that are jointly operated by the ribbon-spool-feeding mechanism. 75
- 15 13. In a typewriting machine, the combination with a carriage having a platen, a spool-fed ribbon, a line-space mechanism, and a spool-feeding mechanism operatively connected to the line-space mechanism to feed a 80
- 20 ribbon to the typing line at each line-spacing movement of the platen, of ribbon-clamping mechanism operative to hold the ribbon stationary under a spool-feeding tension, and means operable by the line-spacing of the 85
- 25 platen to simultaneously release the clamped ribbon and rotate a spool to feed the ribbon, said ribbon-clamping mechanism including normally operative clamps and clamp-releasing members mounted upon the carriage, each 90
- 30 clamp-releasing member having separate connections that are jointly operated by the ribbon-spool-feeding mechanism. 95
14. In a typewriting machine, the combination with a carriage having a platen, a 100
- 35 spool-fed ribbon, a reciprocating line-space mechanism, and a spool-feeding mechanism operatively connected to the line-space mechanism to feed a ribbon to the typing line at each line-spacing movement of the platen, of ribbon-clamping mechanism operative to 105
- 40 hold the ribbon stationary under a spool-feeding tension, and means operable by the line-spacing of the platen to simultaneously release the clamped ribbon and rotate a spool 110
- 45 to feed the ribbon, said ribbon-clamping mechanism including normally operative clamps and clamp-releasing members mounted upon the carriage, each clamp-releasing member having separate connections 115
- 50 that are jointly operated by the ribbon-spool-feeding mechanism, said connections including cam-disks aligned to each releasing member and secured to a shaft supported by the carriage, and rotatably connected to the reciprocating line-space mechanism. 120
- 55 15. In a typewriting machine, the combination with a carriage having a platen, a spool-fed ribbon, a reciprocating line-space mechanism and a spool-feeding mechanism 125
- 60 operatively connected to the line-space mechanism to feed a ribbon to the typing line at each line-spacing movement of the platen, of ribbon-clamping mechanism operative to hold the ribbon stationary under a spool-feeding tension, and means operable by the line-spacing of the platen to simultaneously release the clamped ribbon and rotate a spool to feed the ribbon, said ribbon-clamping mechanism including normally operative clamps and clamp-releasing members mounted upon the carriage, each clamp-releasing member having separate connections that are jointly operated by the ribbon-spool-feeding mechanism, said connections including cam-disks aligned to each releasing member and secured to a shaft supported by the carriage, said shaft being rotated step by step by a pawl-and-ratchet connection to the reciprocating line-space mechanism. 70
- 65 16. In a typewriting machine, the combination with a carriage having a platen, a spool-fed ribbon, and a line-space mechanism, of a spool-feeding mechanism operatively connected to the line-space mechanism, said spool-feeding mechanism including a longitudinally shiftable shaft, rockable by every line-spacing movement and provided with a pair of duplicate pawls operatively spaced upon the shaft relatively to the ribbon-spoils, the longitudinal shifting of said shaft being so effective that only one pawl at a time becomes operative to feed a ribbon-spool. 80
- 70 17. In a typewriting machine, the combination with a carriage having a platen, a spool-fed ribbon, and a line-space mechanism, of a spool-feeding mechanism operatively connected to the line-space mechanism, said spool-feeding mechanism including a shaft rockable by every line-spacing movement and provided with a pair of duplicate pawls operatively spaced upon the shaft relatively to the ribbon-spoils, whereby only one pawl at a time becomes operative to feed a ribbon-spool, said rock-shaft being shiftable to automatically render either pawl by its position operative or inoperative, and predetermine the feeding direction of the spool-fed ribbon. 90
- 75 18. In a typewriting machine, the combination with a carriage having a platen, a spool-fed ribbon and a line-space mechanism, of a spool-feeding mechanism operatively connected to the line-space mechanism, said spool-feeding mechanism including a shaft rockable by every line-spacing movement and provided with a pair of duplicate pawls operatively spaced upon the shaft relatively to the ribbon-spoils, whereby only one pawl at a time becomes operative to feed a ribbon-spool, said rock-shaft being shiftable in the direction of its axis to bodily shift both pawls and render both pawls alternately operative to feed a ribbon-spool. 100
- 80 19. In a typewriting machine, the combination with a carriage having a platen, a spool-fed ribbon and a line-space mechanism, of a spool-feeding mechanism operatively connected to the line-space mechanism, said spool-feeding mechanism including a shaft 105
- 85 120
- 90 125
- 95 130

rockable by every line-spacing movement and provided with a pair of duplicate pawls operatively spaced upon the shaft relatively to the ribbon-spools, whereby only one pawl at a time becomes operative to feed a ribbon-spool, said rock-shaft being shiftable in the direction of its axis to bodily shift both pawls and render both pawls alternately operative to feed a ribbon-spool, said rock-shaft having detenting means operable in both directions of its shaft without interfering with the rocking movement of the shaft.

20. In a front-strike typewriting machine, the combination with a carriage having a platen operable to feed a pair of superposed work-sheets, and a ribbon to cover the typing line and feedable between the work-sheets, of a ribbon-carrier swingably suspended from the carriage and above the platen, manual means on the carriage operable to swing the carrier vertically, and a guide stationary with the carriage and operatively connected to the carrier to swing the ribbon from the typing line to an inoperative typing position above the typing line and close to the face of the platen.

21. In a front-strike typewriting machine, the combination with a carriage having a platen operable to feed a pair of superposed work-sheets, and a ribbon to cover the typing line and feedable between the work-sheets, of a ribbon-carrier swingably suspended from the carriage and above the platen to present the ribbon in a vertical plane close to the face of the platen at the printing line, manual means on the carriage operable to swing the carrier vertically and guides stationary with the carriage and operatively connected to each side of the carrier to swing the ribbon to an inoperative vertical plane above the typing line and close to the face of the platen to provide for greater clearance for the front insertion of a work-sheet.

22. In a front-strike typewriting machine, the combination with a carriage having a platen, a stationary ribbon-spool mounted at each end of the carriage, and a swingable ribbon-carrier operative to deflect the ribbon from the spools to the typing line, of a rock-shaft supported at each end of the carriage, arms secured to said shaft to suspend the ribbon-carrier and the ribbon close to the typing line, means for rocking said shaft to raise the ribbon to uncover the typing line, and means stationary with the carriage and operable through connections with said carrier, to direct the ribbon from the typing line in an arcuate path close to the platen-face.

23. In a front-strike typewriting machine, the combination with a carriage having a platen, a stationary ribbon-spool mounted at each end of the carriage, and a swingable ribbon-carrier operative to deflect the ribbon from the vertical spools to the horizontal typing line, of a rock-shaft supported at

each end of the carriage to lie parallel with the platen, arms projecting forwardly of said shaft to support the ribbon-carrier and present the ribbon to the typing line, means for rocking said shaft to vibrate the ribbon to cover and uncover the typing line, and means stationary with the carriage that are operable through connections with said carrier, to direct the ribbon to and from the typing line, said means including brackets formed with arcuate slots engageable with studs on the free ends of the carrier.

24. In a typewriting machine, the combination with a carriage having a platen, a ribbon-spool at each end of the carriage, and a ribbon-carrier operative to deflect the ribbon from the spools to the typing line, of a rock-shaft supported at each end of the carriage, arms secured to said shaft operative to support the ribbon-carrier to present the ribbon to the typing line, means for rocking said shaft to vibrate the ribbon to cover and uncover the typing line, and means stationary with the carriage that are operable through connections with said carrier, to define a path for the ribbon to and from the typing line, said means including brackets formed with slots engageable with studs on the carrier, to guide the ribbon in one direction and further including means on the brackets operable to engage cam-faces on the carrier to further guide the ribbon in another direction.

25. In a front-strike typewriting machine, the combination with a carriage having a platen, a vertical ribbon-spool at each end of the carriage, and a ribbon-carrier operative to deflect a manifolding ribbon from the vertical spools to the horizontal typing line, of a horizontal rock-shaft supported at each end of the carriage, forward arms secured to said shaft to pivotally suspend the ribbon-carrier to vertically present the ribbon to the typing line, means for rocking said shaft to vibrate the carrier and permit the ribbon to cover and uncover the typing line, and arcuate slots formed at each carriage end and co-operative with studs on the carrier, to direct the ribbon upwardly and rearwardly close to the platen-face when shifted to an inoperative manifolding position.

26. In a typewriting machine, the combination with a carriage having a platen operable to feed a pair of superposed work-sheets, a ribbon-spool at each end of the carriage above the platen, and a ribbon-carrier having guides at each end thereof to direct the ribbon from each spool to the typing line and between the work-sheets, said ribbon-carrier including a cross-bar, of a protective device for the ribbon in the form of a tape to cover the ribbon and prevent offsetting of typed characters upon the outer work-sheet, said protective device including a carrier for each end of the tape,

each carrier and tape-end being jointly clamped to the cross-bar by a thumb-screw.

27. In a typewriting machine, the combination with a carriage having a platen operable to feed a pair of superposed work-sheets, a ribbon-spool at each end of the carriage above the platen, and a ribbon-carrier having guides at each end thereof to direct the ribbon from each spool to the typing line and between the work-sheets, said ribbon-carrier including a cross-bar, of a protective device for the ribbon in the form of a tape to cover the ribbon and prevent offsetting of typed characters upon the outer work-sheet, said protective device including a carrier for each end of the tape, each carrier including a tape-turning face to direct the end of the tape from the horizontal plane of the ribbon to a tape-clamping position between the cross-bar and the carrier, whereby both carrier and tape may be jointly clamped to the cross-bar.

28. In a typewriting machine, the combination with a carriage having a platen operable to feed a pair of superposed work-sheets, a ribbon-spool at each end of the carriage above the platen, and a ribbon-carrier having guides at each end thereof to direct the ribbon from each spool to the typing line and between the work-sheets, said ribbon-carrier including a cross-bar, of a protective device for the ribbon in the form of a tape to cover the ribbon and prevent offsetting of typed character upon the outer work-sheet, said protective device including a carrier for each end of the tape, each carrier including a tape-turning face to direct the end of the tape from the horizontal plane of the ribbon to a tape-clamping position between the cross-bar and the carrier, whereby both carrier and tape may be jointly clamped to the cross-bar, one of said carriers nearest the center of the carriage having an extension operable to hold the center of the ribbon in alignment with the protective tape.

29. In a typewriting machine, the combination with a carriage having a platen operable to feed a wide work-sheet and a superposed narrow work-sheet, a ribbon-spool at each end of the carriage, and a ribbon-carrier operative to deflect the ribbon from the spools to the typing position and between the two work-sheets, of a ribbon-shifting shaft supported by the carriage and operatively supporting the ribbon-carrier, a rock-shaft supported by the carriage at the rear of the platen, paper-fingers carried by the rock-shaft and positioned to hold the edges of the wide work-sheet against the platen, and connections between the ribbon-shifting shaft and the paper-finger rock-shaft, whereby the raising of the ribbon to a sheet-removing position for the wide work-sheet will also raise the paper-fingers from the platen,

or when the ribbon is shifted to an inoperative position above the typing line for the insertion or removal of a narrow work-sheet, the paper-fingers will remain in paper-holding position against the wide work-sheet.

30. In a typewriting machine, the combination with a carriage having a platen, a spool-fed ribbon, and a ribbon-carrier swingably mounted upon the carriage-ends and manually operable to shift a line-length section of the ribbon between the spools to cover and uncover the typing line of the platen, of releasable means mounted upon each end of the carrier and operative to hold the line-length section of the ribbon under a spool-fed non-sagging tension at all shift positions of the carrier.

31. In a typewriting machine, the combination with a carriage having a platen, a spool-fed ribbon, and a ribbon-carrier swingably mounted upon the carriage-ends and manually operable to shift a line-length section of the ribbon between the spools to cover and uncover the typing line of the platen, of releasable means mounted upon each end of the carrier and operative to hold the line-length section of the ribbon under a spool-fed non-sagging tension at all shift positions of the carrier, and means only effective while the ribbon is covering the typing line to release the ribbon to be fed by the ribbon-feeding spool.

32. In a typewriting machine, the combination with a carriage having a platen, a spool-fed ribbon, and a ribbon-carrier swingably mounted upon the carriage-ends and manually operable to shift a line-length section of the ribbon between the spools to cover and uncover the typing line of the platen, of releasable means mounted upon each end of the carrier and operative to hold the line-length section of the ribbon under a spool-fed non-sagging tension at all shift positions of the carrier, and manual means operatively connected to jointly release the ribbon and feed a ribbon-spool.

33. In a typewriting machine, the combination with a carriage having a platen, a spool-fed ribbon, and a ribbon-carrier swingably mounted upon the carriage-ends and manually operable to shift a line-length section of the ribbon between the spools to cover and uncover the typing line of the platen, of releasable means mounted upon each end of the carrier and operative to hold the line-length section of the ribbon under a spool-fed non-sagging tension at all shift positions of the carrier, and manual means operatively connected to jointly release the ribbon and determine a spool-fed direction for the ribbon.

34. In a typewriting machine, the combination with a carriage having a platen, a spool-fed ribbon, and a ribbon-carrier swingably mounted upon the carriage-ends and

manually operable to shift a line-length section of the ribbon between the spools to cover and uncover the typing line of the platen, of releasable means mounted upon each end of the carrier and operative to hold the line-length section of the ribbon under a spool-fed non-sagging tension at all shift positions of the carrier, and manual means operatively connected to release the ribbon and determine 10 a spool-fed direction for the ribbon-feed and the extent of ribbon-feed.

35. In a typewriting machine, the combination with a carriage having a platen, a spool-fed ribbon, and a ribbon-carrier swingably mounted upon the carriage-ends and manually operable to shift a line-length section of the ribbon between the spools to cover and uncover the typing line of the platen, of releasable means mounted upon each end of the carrier and operative to hold the line-length section of the ribbon under a spool-fed, non-sagging tension at all shift positions of the carrier, and manual means operatively connected to release the ribbon, determine the 25 spool-fed direction of ribbon-feed, and the extent of ribbon-feed, and then restore the ribbon-holding means during a continuous movement of said manually-operated means.

36. In a typewriting machine, the combination with a carriage having mounted thereon a platen, a line-space mechanism, a ribbon spool-fed by the line-space mechanism, and a swingable ribbon-carrier constructed to present a line-length section of ribbon to the 30 typing line of the platen, of ribbon-clamping means mounted upon each side of the carrier and operative to hold a spool-fed, non-sagging tension in the line-length section of the ribbon at all positions of said carrier, and 35 means actuated by the line-space mechanism and connectible to release the ribbon-clamping means only when the ribbon covers the typing line of the platen and a joint line-spacing and ribbon-feeding operation is to 40 be effected.

37. In a typewriting machine, the combination with a carriage having mounted thereon a platen, a line-space mechanism, a ribbon spool-fed by the line-space mechanism, and 45 a swingable ribbon-carrier constructed to present a line-length section of ribbon to the typing line of the platen, of ribbon-clamping means mounted upon each side of the carrier and operative to hold a spool-fed, non-sagging tension in the line-length section of the 50 ribbon at all positions of said carrier, mechanism actuated by the line-space mechanism and operative to release the ribbon-clamping means, while the ribbon covers the typing 55 line, to actuate the ribbon-feeding spool, and other mechanism operative when the ribbon does not cover the typing line to disconnect the ribbon-feeding spool from the line-space mechanism.

60 38. In a typewriting machine, the combi-

nation with a carriage having a platen, a spool-fed ribbon, and a ribbon-carrier swingably mounted upon the carriage and manually operable to shift a line-length of the ribbon to cover and uncover the typing line of the 70 platen, of ribbon-clamping means on each side of the carrier operative to maintain a spool-fed tension throughout the line-length section of the ribbon at any shift position of the ribbon-carrier, and manually-operable 75 means connectible at will to release the ribbon-clamping means while the ribbon covers the typing line.

39. In a typewriting machine, the combination with a carriage having a platen operable to feed a wide work-sheet and a superposed narrow work-sheet, ribbon-spools, one spool at each end of the carriage, a swingable ribbon-carrier operative to deflect the ribbon from the spools to the typing line of the platen and between the two work-sheets, and manual means operable to swing the ribbon-carrier to and from the typing line and between the work-sheets, of a rock-shaft supported by the carriage-ends, sheet-holding means adjustable along said rock-shaft to hold the edges of the wide work-sheet against the platen, and connections between the ribbon-carrier and said rock-shaft operable to rock said shaft and lift the sheet-holding means to release the work-sheet when the ribbon-carrier and ribbon are raised above the typing position to a sheet-inserting position.
